UNITED STATES PATENT OFFICE.

HENRY KAPPELE, OF MATTEAWAN, NEW YORK, ASSIGNOR OF ONE-HALF TO JOHN J. BRADLEY, OF MATTEAWAN, NEW YORK.

DOOR-FASTENER.

SPECIFICATION forming part of Letters Patent No. 767,566, dated August 16, 1904.

Application filed May 27, 1904. Serial No. 210,041. (No model.)

To all whom it may concern:

Be it known that I, HENRY KAPPELE, a citizen of the United States, residing at Matteawan, Dutchess county, State of New York, have invented new and useful Improvements in Door-Fasteners, of which the following is a specification.

This invention relates to a fastener of simple construction which will securely lock a door from the inside of a room.

In the accompanying drawings, Figure 1 is a horizontal section of a door provided with my improved fastener. Fig. 2 is a face view of the fastener, showing it locked; Fig. 3, a plan of Fig. 2; Fig. 4, a face view of the fastener with the catch withdrawn; Fig. 5, a plan with the catch withdrawn and the latch swung back; and Fig. 6, a cross-section on line 6 6, Fig. 2.

The letter *a* represents a face-plate adapted to be attached to the door-frame *A* by screws *a'*. From plate *a* extend a pair of parallel posts *a''*, to which is hinged a latch *c*, adapted to be projected over the edge of door *B*. In order to hang the latch to the posts the former is provided with a knuckle *c'*, through which passes a pintle *d*, journaled in the posts *a''*. The knuckle *c'* has a squared lower face *c''*, which is set off from plate *a*, so that a rear-

wardly-opening recess *e* is formed intermediate posts *a''* and between plate *a* and squared face *c''* of knuckle *c'*.

To the plate *a* there is pivoted at *f'* a catch *f*, having handle *f''* and adapted to enter recess *e*.

In use the latch *c* is thrown across the edge of door *B*, and the catch *f* is swung inward to enter recess *e*, Figs. 2 and 3. The latch will thus be locked against turning and by extending rigidly across the door will prevent the latter from being opened. To release the door the catch *f* is withdrawn, Fig. 4, and the latch *c* is swung back over plate *a*, Fig. 5, when the door may be freely opened.

What I claim is—

A door-fastener composed of a plate, posts projecting therefrom, a hinged latch having a squared knuckle intermediate the posts and above the plate to form an intervening recess, and a pivoted catch adapted to engage said recess, substantially as specified.

Signed by me at Matteawan, New York, this 25th day of May, 1904.

HENRY KAPPELE.
